UNITED STATES PATENT OFFICE.

GEORGE STEIN, OF NEW YORK, N. Y.

PORTABLE ELECTRIC HAND-LAMP.

SPECIFICATION forming part of Letters Patent No. 760,657, dated May 24, 1904.

Application filed July 18, 1903. Serial No. 166,130. (No model.)

To all whom it may concern:

Be it known that I, GEORGE STEIN, a citizen of the United States, residing at the borough of Brooklyn, city of New York, county of 5 Kings, and State of New York, have invented certain new and useful Improvements in Portable Electric Hand-Lamps, of which the following is a specification, reference being had therein to the accompanying drawings, which 10 form a part thereof.

My invention relates to portable electric hand-lamps, and more particularly to that class thereof adapted to be used to produce an intermittent light.

15 The object of the invention is to provide a portable electric hand-lamp of this character wherein the various parts will be so assembled as to produce a neat and compact article, wherein the circuit will be normally open, and 20 wherein the switch or circuit-closer will be so constructed and arranged as to prevent the accidental closing of the circuit, as when a lamp or lamps are stored or packed for shipment or not in use.

25 The invention consists in the novel features of construction hereinafter set forth and described, and more particularly pointed out in the claims hereto appended.

Referring to the drawings, Figure 1 is an 30 elevation of a portable electric hand-lamp embodying my invention; and Fig. 2 is a sectional elevation thereof, showing the battery, the spring in the closure-cap, the lamp, and the lens in elevation.

35 Like letters refer to like parts in both of the views.

In the accompanying drawings, *a* indicates 40 an outer casing, preferably tubular in form and composed of fiber or some equivalent insulating material. About each end of this tube *a* is riveted or otherwise permanently secured a metallic band *b* and *c*, respectively, each provided with exterior screw-threads. These bands are electrically connected in a 45 manner to be hereinafter described and serve, respectively, as a means for securing a metallic reflector *d* and a bull's-eye lens *e* in one end of this casing *a* and for confining a removable primary or secondary battery *f* in the 50 other end thereof. The reflector *d* is prefer-

ably of the parabolic type having an outwardly-flared flange *d'* about the mouth thereof. The dimensions of the body of this reflector are such as to permit it to pass freely within the open end of the casing *a* until the 55 flange *d'* rests upon the outer and exposed edge of the ring *b* in a manner to insure a good base for soldering these parts together and also to insure a good electrical connection between said band and said reflector. The base of the 60 reflector is provided with an integral screw-threaded neck or lamp-socket *d''*, open at both ends and adapted to receive the terminal plug *g'* of an incandescent electric lamp *g* of ordinary and well-known construction and to permit the terminal butt *g''* thereof to be thrust 65 into the outer casing *a* behind said reflector.

To provide for the convenient insertion, removal, and replacement of the lamp *g* and to increase the efficiency of the lamp and reflector, 70 as well as to protect said lamp, the lens *e* is held in place to close the mouth of the reflector by means of a screw-threaded ring *i*, having an inwardly-turned flange *i'*, which engages the lens and which is adapted to engage the screw- 75 threads on the band *b*, which are provided for that purpose. The opposite or rear end of the casing *a* is closed by means of a metallic closure-cap *h*, held in place by and electrically connected with the band *c* by means of screw-threads 80 thereon. A spring *h'*, carried by the cap *h*, is permanently attached thereto in a manner to have good electrical contact therewith. The battery *f* is disposed within the outer casing between the said cap *h* and the reflector *d*, the 85 opposite poles thereof being, respectively, in electrical contact with the butt *g''* of the lamp *g* and the spring *h'*, which serves to maintain it in such contact, as well as to form a part of the electrical circuit. The battery may be of any 90 desired construction and arrangement, having an insulating-envelop therefor.

The electrical connection between the bands *b* and *c* consists of a conducting wire or strip *k*, one end of which is permanently attached to 95 the band *c* by being placed in intimate surface contact therewith and soldered thereto or otherwise held in such contact, an escutcheon *l*, riveted to the outside of said casing, to which the other end of said conducting wire or strip *k* 100

is electrically connected, a second conducting wire or strip *m*, one end of which is electrically connected to the band *b* in the same manner employed to establish electrical connection between the band *c* and wire or strip *k* and the other end of which is electrically connected with a stud or button *n*, adjacent to the escutcheon *l*, and a switch *o*, carried by the said escutcheon and adapted to engage the stud or button *n* to close the circuit. The switch *o* comprises a spring-tongue *o'*, normally out of contact with the stud or button *n* and preferably provided with an enlarged portion to increase the bearing-surface, and thus facilitate its use. It has been found that a spring-tongue as ordinarily employed in an electrical switch used in this and similar relations is so exposed that in case of a weight being inadvertently placed thereon, even if it were merely the result of laying the lamp down with the switch beneath, it is pressed down upon the stud or button *n*, and the circuit being thus closed the battery energy is wasted and the lamp burned out, even if the entire battery is not exhausted. To prevent this accidental closing of the circuit, I provide an elevated guard adjacent to the spring-tongue *o'*, which serves to hold this tongue out of contact with adjoining objects. This guard is of such height and is placed in such a relation to the spring-tongue *o'* that one end of the entire lamp is raised sufficiently to prevent the said tongue from coming in contact with any flat or substantially flat surfaces upon which it rests or with which it contacts. Preferably this guard takes the form of a loop *o''*, made integral with the spring-tongue *o'* and arranged between it and the rivets, securing the whole to the escutcheon *l*. Both ends of this loop bear firmly against said escutcheon, and all spring action is beyond this loop. The height of the loop is such that a straight line drawn therefrom to any point on the band *b* would not touch the spring-tongue *o'*. The arrangement heretofore described admits of a convenient assembling of parts. The switch *o* is first mounted on the escutcheon *l*, and the wires *k* and *m* are respectively attached to said escutcheon and button or stud *n* and then passed through holes in the casing *a* provided for this purpose, and the said escutcheon and stud are then secured to said outer casing. The free ends of said conducting wires or strips are then extended along the inside of this casing to the exposed ends thereof, where they are respectively attached to the bands *c* and *b*, as described. These bands are thereafter secured in position on said outer casing *a*, preferably by means of rivets. The reflector *d* is then slipped in the end of the casing, and the flange *d'* is soldered to the outer edge of the band *b*. The manner of applying the remaining parts is apparent. The electrical conditions present are also self-evident and require no detailed explanation.

The employment of the screw-threaded band *b* and ring *i* greatly facilitates the replacement of a burned-out lamp and also compensates for the irregularity in the thickness of commercial lenses. The attachment of the closure-cap *h*, with its spring *h'*, by means of screw-threads, also admits of the regulation of the tension of the said spring, and hence the pressure upon the battery and the part in which the opposite pole thereof is in contact. This screw-threaded joint also permits the use of batteries which vary somewhat in their length under exactly similar conditions. The arrangement of the spring-tongue *o'* and guard *o''* serves to effectually prevent the accidental closing of the circuit when lamps are in stock, packed for shipment, or when lying around when not in use.

It is not my intention to limit my invention to the precise details of construction as herein shown and described, as it is apparent that there may be many variations in the manner of combining the various elements necessarily entering into the manufacture of such a lamp without departing from the spirit and scope of the invention.

Having described the invention, what I claim as new, and desire to have protected by Letters Patent, is—

1. In a portable electric hand-lamp, the combination of an outer casing, a contained battery, a translating device carried by said casing, electrical connections between the opposite poles of said battery and the respective terminals of said translating device including therein a normally open circuit-closer arranged exteriorly of said casing, comprising a fixed contact, a depressible tongue, and an elevated guard adjacent to said circuit-closer whereby pressure on said tongue from contact with adjoining objects is prevented.

2. In a portable electric hand-lamp, the combination of an outer casing, a contained battery, a translating device carried by said casing and electrical connections between the opposite poles of said battery and the respective terminals of said translating device including a normally open circuit-closer arranged exteriorly of said casing comprising a spring-tongue secured to said casing, a loop integral therewith arranged between said tongue and its securing means and of a height to prevent pressure on said tongue from adjoining objects and a button or stud disposed adjacent to said spring-tongue whereby the circuit may be closed.

3. In a portable electric hand-lamp, the combination of an outer casing, a contained battery, a metallic reflector carried within one end of said casing, a screw-threaded metallic band about the end of said casing, a lens closing the mouth of said reflector, a screw-threaded ring adapted to removably secure said lens in position, an electric lamp mounted in said reflector, the butt of said lamp having

electrical contact with one pole of said battery, a screw-threaded metallic band about the other end of said casing, a metallic closure-cap removably connected to said last-mentioned band, a spring carried by said cap and acting upon and having electrical contact with the other pole of said battery, an escutcheon mounted on the outside of said casing, a normally open circuit-closer arranged 5 exteriorly of said casing comprising a spring-tongue secured to said escutcheon a loop integral therewith arranged between said tongue and its securing means and of a height to prevent pressure on said tongue from contact

with adjoining objects, a button or stud disposed adjacent to said spring-tongue whereby the circuit may be closed and conducting strips or wires connected with said bands and said escutcheon and said button or stud respectively.

20

In witness whereof I have hereunto affixed my signature, this 18th day of April, 1903, in the presence of two witnesses.

GEORGE STEIN.
